CHRISTMAS TREE ORNAMENT

Dario Moranduzzo, Via Aretina 161,
Florence, Italy

Filed Oct. 22, 1965, Ser. No. 87,795

Term of patent 14 years

(Cl. D29—1)

I claim:

The ornamental design for a Christmas tree ornament, as shown and described.
